UNITED STATES PATENT OFFICE

ALVIN W. PUFFER, OF MEDFORD, MASSACHUSETTS, ASSIGNOR TO PUFFER MANUFACTURING COMPANY, OF WINCHESTER, MASSACHUSETTS, A CORPORATION OF MAINE

SODA FOUNTAIN CABINET

Application filed February 13, 1928. Serial No. 253,958.

This invention relates to a soda fountain cabinet and has for its object to provide a cabinet of maximum efficiency, which can be installed and operated at minimum cost and one in which the cooling compartment for syrup jars and the like is subjected, without the use of a pump, to a temperature approximating the freezing point of water by means of a body of liquid refrigerant external to said cooling compartment and maintained at a temperature below the freezing point of water.

To this end, the cabinet is provided with a container for a body of liquid refrigerant, such as brine, which container is provided with a substantially horizontal member located adjacent to the syrup-jar-cooling compartment and substantially of the same length as the cooling compartment, and the other member of said container is in open communication with the first-mentioned member and forms a reservoir or well for the liquid refrigerant.

The reservoir or well may and preferably will contain an expansion chamber for maintaining the body of liquid refrigerant in the container at a refrigerating temperature.

The substantially horizontal member of the container may have its end removed from the well connected with the latter near the bottom thereof for thermally circulating the body of liquid refrigerant through the container as will be described.

The invention is particularly serviceable when embodied in a substantially long cabinet having a plurality of main compartments, and in the present instance it is shown as embodied in a relatively long cabinet having a refrigerating compartment for containing ice cream cans and like receptacles whose contents are to be maintained in solid form, and a second compartment for receiving milk and like bottled goods whose contents are to be maintained in liquid form, and having the syrup-jar-cooling compartment extended for a substantial part of the length of the cabinet, and open at its top for the ready insertion and removal of the syrup jars by the operator dispensing soda.

These and other features of this invention will be pointed out in the claims at the end of this specification.

Fig. 1 is a plan view of a soda fountain embodying this invention;

Fig. 2, a rear elevation of the soda fountain shown in Fig. 1;

Fig. 3, a section on the line 3—3, Fig. 1, looking toward the left;

Fig. 4, a section on the line 4—4, Fig. 1, looking toward the right;

Fig. 5, a section on the line 5—5, Fig. 1, looking toward the left, and

Fig. 6, a vertical longitudinal section of the fountain with parts broken away, the section being taken on the irregular line 6—6, Fig. 3.

The soda fountain herein shown as embodying the invention is provided with a substantially oblong cabinet of marble or other suitable material and having the front and rear walls 10, 12, bottom wall 13, suitably shaped end walls 14, 15, and a counter or top wall 16.

The cabinet herein shown is provided with a plurality of main compartments, herein shown as two in number, and marked 17, 18.

These compartments are substantially oblong in shape and are separated from the bottom and upright walls of the cabinet by layers or walls 19 of cork or other heat-insulating material.

The compartments 17, 18 are also separated from each other by a transverse wall 20 of heat-insulating material.

The compartment 17 is designed to have a relatively low refrigerating temperature, preferably about 36° F. and will be herein-after referred to as the refrigerating compartment, whereas the compartment 18 is designed to have a temperature approximating the freezing point and preferably from 32° to 34° F. and will be herein-after designated as the cold compartment.

These different temperatures may be obtained and maintained preferably in a manner as will be described.

The compartment 17 in the form of a tank is filled or substantially filled with brine or other suitable refrigerating liquid.

(see Fig. 4), which is maintained at the proper temperature by an expansion chamber, herein shown as a closed vessel 24 having a series of pipes 25 connected therewith, said vessel being of suitable shape to permit it to be inserted into the tank or compartment 17 through an opening in the rear wall 26 thereof (see Fig. 1), and to be supported by a cover plate 27 which closes the said opening liquid-tight and is secured to the rear wall of the compartment by screws 28 or otherwise.

The expansion chamber 24, 25 is connected by suitable inlet and outlet pipes 29, 30 with a refrigerating unit or plant, which is located outside of the soda fountain and is not herein shown as it may be of any suitable or usual construction.

The cabinet is also provided with a cooling compartment 32, preferably extended substantially the length of the cabinet and open at its top for the reception of syrup jars 33 and the like, and preferably contains a body 34 of water, usually termed "sweet water" into which the syrup jars and the like are partially immersed.

The cooling compartment 32 is also designed to have placed in it containers 35 for charged water and a cooling coil 36 connected with containers 35 and with draft arms 37 located above the top of the cabinet.

The present invention has for its object to subject the cooling compartment 32 to a temperature approximating the freezing temperature of water and maintain it at such temperature without the use of a pump and by means of a body of liquid refrigerant external to said cooling compartment.

To this end the cooling compartment 32 has co-operating with it a container for a body of liquid refrigerant, said container being provided with a member 40 extended lengthwise of the cooling compartment 32, preferably for the entire length of the latter and in proximity thereto, and said container is provided with a second member, preferably in the form of a vertically arranged well or reservoir 41 having its upper end in open communication with the member 40.

The reservoir or well 41 is located within the cabinet at one end thereof and is separated from the cold compartment 18 by a wall 42 of heat-insulating material, and from the walls of the cabinet by the layers 19 of heat-insulating material.

The container member 40 is preferably made so that the refrigerant therein contacts with the bottom wall 43 of the cooling compartment 32 and is herein shown as T-shaped in cross section (see Figs. 3 and 4), and the head of the T-shaped member is preferably arranged so that one side wall 44 thereof forms part of a side wall of the cold compartment 18. The body of liquid refriger-

ant 54 in the container 40, 41, preferably brine, is maintained at a refrigerating temperature, to wit: below the freezing point of water, but which may be below the freezing point only sufficiently to enable the cold 70 imparted to the cooling compartment 32 to maintain the syrup jars 33 cool or at a temperature above but relatively close to the freezing point.

For this purpose it is preferred to provide the reservoir or well 41 with an expansion chamber similar to that used in the refrigerating compartment 17 and comprising a vessel 46 and pipes 47 connected therewith, which expansion chamber is attached to a cover plate 48 secured to the rear wall of the reservoir or well 41.

The expansion chamber 46, 47 may and preferably will be connected with the refrigerating plant or unit outside of the soda fountain, and provision is made for controlling the refrigeration of the expansion chamber 46, 47 independently of the expansion chamber 24, 25 for the compartment 17, and to this end the expansion chamber 46, 47 is provided with an inlet pipe 50 and an outlet pipe 51, and the inlet pipe 50 is tapped off from the inlet pipe 29 for the expansion chamber 24, 25 and is provided with an expansion valve 52, preferably a thermostatically-operated valve of known construction, which may be located in the compartment 18, as represented in Fig. 3, and is responsive to temperature changes in said compartment.

Preferably the expansion valve 52 is set or adjusted to close when the temperature of the compartment 18 falls to 32° F. and to open when it reaches 34° F.

The body of liquid refrigerant 54 in the container may be a static body or it may be made to circulate thermally through the container, as herein shown.

To this end, the end of the container member 40 remote from the well or container member 41 is connected by a downward-inclined pipe 57 with the well 41 near the bottom of the latter, and said pipe is preferably arranged to contact with an outside wall of the refrigerating compartment 17 and of the cold compartment 18 (see Figs. 2, 3 and 4). As a result of this arrangement, the liquid refrigerant 54 in the portion of the pipe 57 in contact with the refrigerating compartment 17 is subjected to a much lower temperature than is the rest of the refrigerant, and is thereby caused to circulate from the well 41 through the jacket or member 40 and the pipe 57 back to the well 41.

This circulation may be termed a thermal circulation.

It will be seen that the cooling compartment 32 is cooled by a body of liquid refrigerant external to said compartment and

without the use of a pump for such purpose, and that said cooling compartment is subjected to such body of refrigerant for substantially its entire length, and that the body of liquid refrigerant may be maintained at a temperature close to the freezing point and at such relatively low temperature as to ensure the contents of the syrup jars or the like in the cooling compartment being kept cool under all conditions of use.

The hollow leg portion 63 of the refrigerant container is encased in the heat-insulating material 19 (see Figs. 3 and 4).

The compartment 17 is designed to receive cans 60 containing ice cream and the like, which are placed in auxiliary tanks or receptacles 61 located in the compartment 17 with the upper ends above the level of the brine in said compartment, as represented in Fig. 4.

One embodiment of the invention is herein shown, but it is not desired to limit the invention to the construction shown.

What I claim is:

1. In a soda fountain cabinet, in combination, a cooling compartment extended in the direction of the length of the cabinet, a container for a body of liquid refrigerant having members arranged at an angle to each other and one of which is extended in the direction of the length of the cooling compartment and external thereto to have the liquid refrigerant therein contact with the bottom wall of said cooling compartment, and the other of which forms a well, a pipe connecting the lower end of the said well with the first named member at a point removed from the said well, and a low temperature refrigerating compartment thermally connected with said pipe at a point removed from said well.

2. In a soda fountain cabinet, in combination, a cooling compartment for syrup jars and the like, a container for a body of liquid refrigerant external to said cooling compartment and extended substantially the length of the latter and having the refrigerant therein contacting with a wall of said compartment to cool the same, and means for maintaining the body of liquid refrigerant within the container at a refrigerating temperature, and a low temperature refrigerating compartment thermally connected with said container for effecting circulation of the liquid refrigerant therein.

3. In a soda fountain cabinet, in combination, a relatively low temperature refrigerating compartment, a cooling compartment for syrup jars and the like, a container for liquid refrigerant external to said cooling compartment and thermally connected therewith and extended lengthwise thereof, below the same, and the pipe communicating with the said container to receive liquid refrigerant and arranged with relation to the

said refrigerating compartment external thereto to have the liquid refrigerant in said pipe subjected to the low temperature of said refrigerating compartment.

4. In a soda fountain cabinet, in combination, a cooling compartment extended lengthwise of said cabinet, a container for liquid refrigerant located below said cooling compartment and having its upper wall forming the bottom wall of said cooling compartment, and a refrigerating compartment non-communicating with said container but cooperating therewith to lower the temperature of the liquid refrigerant in said container.

5. In a soda fountain cabinet, in combination, a container for liquid refrigerant comprising a substantially horizontal member, a vertically arranged member or well with which one end of said horizontal member communicates near the top of said well, and a return pipe connecting the opposite end of said horizontal member with the said well near the bottom thereof, a cooling compartment arranged with relation to said substantially horizontal member to be cooled by the liquid refrigerant therein, and a refrigerating compartment co-operating with said return pipe to subject refrigerant in the latter to a relatively low temperature and thereby establish and maintain circulation of said liquid refrigerant through said conduit.

6. In a soda fountain cabinet, in combination, a cooling compartment extended lengthwise of said cabinet, a container for the circulation of a liquid refrigerant having a hollow substantially T-shaped section arranged below said cooling compartment, and co-operating therewith for cooling it, and a cold compartment having a portion of one of its walls formed by a wall of the head of the T-shaped section of said container.

7. In a soda fountain cabinet, in combination, a relatively low temperature refrigerating compartment, and a cold compartment separated by a wall of heat-insulating material, an expansion chamber in said relatively low temperature refrigerating compartment, a cooling compartment extended lengthwise of said cabinet for substantially the length of said refrigerating and cold compartments, a container for liquid refrigerant external to said cooling compartment and comprising a substantially horizontal member extended lengthwise of said cooling compartment and co-operating therewith to cool the same, and a substantially vertical member or well with the upper end of which said horizontal member is connected, a return pipe connecting the opposite end of said horizontal member with the said well near the bottom of the latter, said return pipe having a portion

thereof arranged with relation to the low temperature refrigerating compartment to be subjected to the relatively low temperature thereof and effect circulation of the liquid refrigerant through said container, and an expansion chamber in said well.

8. In a soda fountain cabinet, in combination, a relatively low temperature refrigerating compartment, and a cold compartment separated by a wall of heat-insulating material, an expansion chamber in said relatively low temperature refrigerating compartment, a cooling compartment extended lengthwise of said cabinet for substantially the length of said refrigerating and cold compartments, a container for liquid refrigerant external to said cooling compartment, and co-operating with the low temperature refrigerating compartment to effect circulation of liquid refrigerant in said container, the latter having a substantially horizontal member extended lengthwise of said cooling compartment to cool the same and a substantially vertical well with the upper end of which said horizontal member is connected, and an expansion chamber in said well.

9. In a soda fountain cabinet, in combination, a relatively low temperature refrigerating compartment, a cold compartment substantially in line with said refrigerating compartment, an expansion chamber in said refrigerating compartment, a cooling compartment extended lengthwise of said cabinet substantially parallel with said refrigerating and cold compartments and open at its upper portion for the insertion of syrup jars and the like, a container for liquid refrigerant having a portion thereof extended lengthwise of said cooling compartment and thermally connected therewith to cool the same and provided with a substantially vertical portion constituting a well for said liquid refrigerant, and an expansion chamber in said well, the portion of said container extended lengthwise of said cooling compartment being arranged with relation to said refrigerating compartment to be cooled thereby and effect circulation of the liquid refrigerant in said container.

10. In a soda fountain cabinet, in combination, a relatively low temperature refrigerating compartment, a cold compartment substantially in line with said refrigerating compartment, an expansion chamber in said refrigerating compartment, a cooling compartment extended lengthwise of said cabinet substantially parallel with said refrigerating and cold compartments and open at its upper portion for the insertion of syrup jars and the like, a container for liquid refrigerant having a portion thereof extended lengthwise of said cooling compartment and thermally connected therewith to cool the same and provided with a

substantially vertical portion constituting a well for said liquid refrigerant, the portion of said container extended lengthwise of said cooling compartment being arranged with relation to said refrigerating compartment to be cooled thereby and effect circulation of the liquid refrigerant in said container.

11. In a soda fountain cabinet, in combination, a relatively low temperature refrigerating compartment, a cold compartment substantially in line with said refrigerating compartment, an expansion chamber in said refrigerating compartment, a cooling compartment extended lengthwise of said cabinet substantially parallel with said refrigerating and cold compartments and open at its upper portion for the insertion of syrup jars and the like, a container for liquid refrigerant having a portion thereof extended lengthwise of said cooling compartment and thermally connected therewith to cool the same and provided with a substantially vertical portion constituting a well for said liquid refrigerant, said container being arranged in proximity with said refrigerating compartment to be cooled thereby and effect circulation of liquid refrigerant therein.

12. In a soda fountain cabinet, in combination, a relatively low temperature refrigerating compartment, a cold compartment substantially in line with said refrigerating compartment, an expansion chamber in said refrigerating compartment, a cooling compartment extended lengthwise of said cabinet substantially parallel with said refrigerating and cold compartments and open at its upper portion for the insertion of syrup jars and the like, a container for liquid refrigerant having a portion thereof extended lengthwise of said cooling compartment and provided with a substantially vertical portion constituting a well for said liquid refrigerant, and an expansion chamber in said well, said container being thermally connected with all of said compartments for effecting circulation of the liquid refrigerant therein and for effecting cooling of the cold compartment and said cooling compartment.

13. In a soda fountain cabinet, in combination, a relatively low temperature refrigerating compartment, an expansion chamber in said refrigerating compartment, a cooling compartment capable of containing a liquid and open at its upper portion for the insertion of syrup jars and the like, a container for a body of liquid refrigerant external to said cooling compartment and co-operating therewith to cool the same and thermally connected with said low temperature refrigerating compartment, and an expansion chamber located in said external

container for refrigerating the body of liquid refrigerant therein.

14. In a soda fountain cabinet, in combination, a relatively low temperature refrigerating compartment, an expansion chamber in said refrigerating compartment, a cooling compartment capable of containing a liquid and open at its upper portion for the insertion of syrup jars and the like,
10 a container for a body of liquid refrigerant external to said cooling compartment and co-operating therewith to cool the same, and means for effecting a thermal connection between said container and said low temperature refrigerating compartment for effecting a circulation of the liquid refrigerant in said container.

15. In a soda fountain cabinet, in combination, a relatively low temperature refrigerating compartment, an expansion chamber in said refrigerating compartment, a cooling compartment provided with an elongated portion, a container for a body of liquid refrigerant also having an elongated portion thermally connected with the elongated portion of said cooling compartment to cool the same, and means for thermally connecting said container with the low temperature refrigerating compartment
25 for effecting a circulation of the liquid refrigerant in said container.

16. In a soda fountain cabinet, in combination, a cooling compartment, a closed conduit for liquid refrigerant external to
30 said cooling compartment and having a member below the bottom wall of said compartment to cooperate and in thermal connection therewith, and a low temperature refrigerating compartment cooperating with a portion of said closed conduit to effect circulation of the liquid refrigerant therein.

In testimony whereof, I have signed my name to this specification.

ALVIN W. PUFFER.
